UNITED STATES PATENT OFFICE

MEASURING AND DISPENSING PACKAGE

Ernest J. Biskamp, San Antonio, Tex.

Application May 2, 1942, Serial No. 441,495

15 Claims.

(Cl. 222—455)

This invention relates to a measuring and dispensing package for various kinds of granular or powdered material such as sugar, coffee, soap, etc., and more particularly to a package of this type in the nature of a folded blank box formed from cardboard or the like.

The present application is a continuation in part of my prior co-pending application S. N. 433,813, filed March 7, 1942.

Among the objects of the present invention is to devise a construction of measuring device which will be simple and cheap to produce and which is readily assembled with the usual form of folded blank box now in commercial use.

To this end, I propose to form the parts of my improved measuring device in such manner that the assembled box containing the measuring device may be packed and shipped in flat or collapsed condition.

The type of box for which my invention is especially adapted is that known as a folded blank tubular box, that is to say, a box which is assembled at the factory in flat collapsed form, and then, at the time of filling, is expanded into tubular form with open ends. Such ends are then closed by folding over end flaps or the like.

A specific object of the invention is to provide a measuring device in the form of a collapsible rectangular receptacle, which is enclosed within the folded blank box in collapsed form, and which automatically opens to operative condition when the box is opened up into tubular form, preparatory to filling.

In order that the invention may be readily understood, reference is had to the accompanying drawings, forming part of this specification, and in which—

Fig. 1 is a view of the blank from which I form my improved measuring receptacle.

Fig. 2 is a similar view showing the blank as it appears after having been folded to form the receptacle, but in collapsed condition.

Fig. 3 is a transverse section on the line 3—3 of Fig. 2, looking in the direction of the arrows.

Fig. 4 is a perspective view showing the complete receptacle as it appears when in open condition.

Fig. 5 is a view of the box blank with my improved measuring receptacle assembled thereon in collapsed position.

Fig. 6 is a transverse section, substantially on the line 6—6 of Fig. 5, and showing in dotted lines the position of parts of the box blank after being folded.

Fig. 7 is a fragmentary section on an enlarged

scale, substantially on the line 7—7 of Fig. 5, looking in the direction of the arrows;

Fig. 8 is a transverse section similar to Fig. 6, but on a somewhat enlarged scale, showing the assembled box and measuring device in flat, collapsed form, ready for shipment;

Fig. 9 is a similar section, but showing the assembly as it appears when partly opened up;

Fig. 10 is a similar view, showing the assembly as it appears when fully opened up into tubular form, ready for filling;

Fig. 11 is a fragmentary section on the line 11—11 of Fig. 10, looking in the direction of the arrows;

Fig. 12 is a section substantially on the line 12—12 of Fig. 11, looking in the direction of the arrows, and showing the delivery corner of my improved package, after having been filled;

Fig. 13 is a similar view, but showing the package inverted to discharge position.

Fig. 14 is a fragmentary view, similar to Fig. 2, but showing a slightly modified construction.

Fig. 15 is a section on the line 15—15 of Fig. 14, looking in the direction of the arrows; and

Fig. 16 is a fragmentary view similar to Fig. 4, but showing the construction illustrated in Figs. 14 and 15.

Referring to the drawings in detail and more particularly first to Figs. 1 to 4 inclusive, I have illustrated in these figures my improved measuring receptacle. This is formed of a folded blank of cardboard or the like. As shown in Fig. 1, the blank comprises side wall panels 1 and 2, and edge wall panels 3 and 4, these panels being separated by the score lines *a*, *b* and *c* as shown.

Projecting from the side of the panel 1 is an extension 5 of a width substantially equal to twice the width of the panels 3 and 4, for a purpose which will be hereinafter described, this extension 5 being separated from the panel 1 by a score line *d*.

Also projecting downwardly from the end of panel 1 is a panel or extension 6 of the same width and preferably of somewhat greater length, this extension 6 being separated from the panel 1 by means of a score line *e*.

The blank thus constructed is then folded about the score line *a* as shown in Fig. 2, and the panel 4 is folded back upon the panel 2 about the score line *c*, so that the extension 5 overlaps the folded over panel 4. The panel 4 is then secured to the under side of the extension 5 by means of a suitable adhesive, as indicated in dotted lines at 4^a. Figs. 2 and 3 show the appearance of the receptacle after having been folded

and glued as above described, and in flat or collapsed condition.

Fig. 4 shows the appearance of the receptacle when opened up into operative condition, this view showing the opposite side of the receptacle from that illustrated in Fig. 2. From an inspection of Fig. 4 it will be seen that the extension 5 projects up beyond the panel 2 a distance substantially equal to the width of the panels 3 and 4.

In Fig. 5 I have illustrated a common commercial type of folded box blank with my improved measuring receptacle assembled thereon. The box blank comprises edge panels or walls 11 and 12, and side panels or walls 13 and 14, these being separated by score lines f, g and h, as usual. These panels are extended at the top and bottom of the blank to form end flaps 11', 12', 13' and 14', adapted to be folded over to constitute the end walls of the box in a well known manner.

Projecting from the side of panel 11 is a narrow panel or sealing strip 15, separated from the panel 11 by a score line i.

My improved measuring receptacle, in the condition shown in Fig. 2, is applied to this box blank in the following manner. The panel 3 is rigidly secured to the panel 13, as by means of a suitable adhesive indicated by dotted lines at 9. When thus applied, the upper edge of the receptacle is positioned to substantially coincide with the fold line between the box panels and the end flaps, and the free edge 5^a of the extension 5 substantially coincides with the fold or score line h, between the panels 12 and 14 of the box blank. At the same time, I apply to the panel 12 a clip or tab 7, preferably of cardboard, and of a length substantially equal to the width of this panel, in such position as to overlie the lower edge of the panel 6. This clip or tab 7 is secured adjacent its lower edge 7^b only, as by means of a suitable adhesive 8, so that the upper portion is free, and is preferably bent slightly outwardly, as about a score line 7^a, so as to provide a space between itself and the panel 12. It will thus be understood that the panel 6 is confined within this space between the tab 7 and the panel 12, but that it is free to slide laterally within this space. In other words, the panel 6 is slidably secured to the panel 12. It will thus be seen that the receptacle, in collapsed form, when applied to the box blank as above described, extends across the fold line g and overlies both panels 12 and 13, and that the width of the panels 1, 2 and 6 is substantially equal to that of panel 12. Panel 6, particularly, should be the full width of panel 12, so that its edges will fit snugly against the panels 13 and 14, when the box is opened up. It will also be noted that the panel 3 of the receptacle is spaced from the fold line g a distance which may be substantially equal to the width of this panel. The relative position of the parts is well illustrated in Figs. 5, 6 and 7.

After having thus assembled the measuring receptacle on the box blank as above described, the panels 11 and 14 of the box blank are then folded over as indicated in dotted lines in Fig. 6, so that the edge of panel 14 overlaps the sealing strip 15, these parts being united by a suitable adhesive, as usual.

Fig. 8 shows the completed assembly, the box being in flat collapsed form and enclosing the receptacle, also in flat collapsed form, and the assembly may thus readily be shipped in this condition from the factory to the user who will fill the box with his product.

Fig. 9 shows the assembly when partially opened up. In moving from the position shown in Fig. 8 to that shown in Fig. 9, it will be understood that the panels 11 and 12 swing upwardly about the fold lines i and h, while at the same time the panels 1 and 2 of the receptacle swing about the hinges a, b, c and d, into the position illustrated. In this connection it will be particularly noted that while the partition walls are fixed at one side to a side wall of the box, as by cementing the panel 3 to such side wall, as shown at 9, the other side of the partition walls, where they are united by the panel 4, are not attached to the box wall 14, but are anchored against relative lateral movement with respect thereto by reason of the engagement of the free edge 5^a of the extension with the fold h of the box. This expedient, whereby the partition walls are cemented to only one wall of the box is an important feature of the invention, since it makes possible the assembly of the measuring device in collapsed condition within the box as described.

Fig. 10 shows the assembly fully opened up, and ready for filling, the parts being brought to this position, from the position of Fig. 9, by a further swinging movement. By reference to Fig. 10 it will be seen that in this final position the panels 1 and 2 of the receptacle constitute partition walls, extending across the box between the side walls thereof in spaced relation, parallel with each other and with the edge wall 12 of the box.

While the panel 3 has been shown and described as spaced from the fold line g a distance substantially equal to its own width, and the extension 5 has been shown and described as projecting the same distance beyond the panel or partition wall 2, so that this partition wall lies midway between the partition wall 1 and the wall 12 of the box, this exact relation is by no means essential. All that is necessary is to have the extension 5 of such length, and the panel 3 so positioned as to space the partition wall 2 from the wall 12 a sufficient distance to provide an ample discharge passageway. This passageway should preferably be at least as wide as that between the partition walls 1 and 2.

It will be now be understood, by reference to Fig. 5, that as the box is opened up as illustrated in Figs. 9 and 10, the panel 6 slides transversely beneath the clip 7. At the same time, as the panel 12 swings upwardly, and the blank begins to fold about the score line g, there is a tendency to bend and slightly cramp the panel 6. To relieve this cramping and facilitate the sliding movement, the corner of the panel 6 may be rounded off as shown at 6^a in Figs. 1, 2, 4 and 5, and, in any event, the panel 6 should be made of relatively flexible material so that it may readily bend to the necessary extent, while the clip 7 should be somewhat resilient, and also preferably scored, as shown at 7^a. Also the clip 7 may be, in some cases, made narrower than illustrated in Fig. 5, although when finely powdered material is being dispensed, it is desirable to have the space at the lower edge of the panel 6 tightly closed throughout its full width, by the clip 7.

By reference to Fig. 12 it will be seen that the panels 2 and 4 extend substantially to the upper end of the box, while the panel 1 is shorter, thus leaving a space 16 above the same, through which material may flow.

Also by reference to Fig. 12 it will be seen that the panel 6, which is disposed at an angle

to the other panels, forms between itself and the panel 12 a chamber into which the material being measured falls, and from which it is discharged through the chamber or passageway between the partition 2 and the wall 12.

Finally, by reference to Fig. 13 it will be seen that when the box is inverted, the fluent material flows in through the space 16 until a definite quantity is trapped in the measuring device. Then when the box is moved to upright position, this trapped material falls down into the chamber formed by the panel 6. Then when the box is again tipped into the position shown in Fig. 13, the material passes through the chamber between the partition 2 and wall 12 and flows out through the discharge opening formed by the usual tear-out tongue 12.

It will be understood from the foregoing that successive measured quantities of material may be discharged from the box by alternately moving the same to upright and inverted positions, in a well known manner.

In Figs. 14, 15 and 16 I have shown a slightly modified construction of the measuring device.

It will be noted that in the construction shown in Figs. 2, 3 and 4, I have illustrated the panel 4 as folded back upon the panel 2, when in collapsed condition, or as extending toward the panel 1 when opened up, as in Fig. 4.

By reference to Figs. 14, 15 and 16, however, it will be seen that in this modified construction the panel 4 remains in the same plane as the panel 2, when in collapsed condition, and is glued directly to the panel 5. When opened up into operative condition, as shown in Fig. 16, it will be seen that this results in the panel 4 extending upwardly from the panel 2, or, in other words, in a direction away from the panel 1.

While in Figs. 2 and 4 I have shown the panel 5 as shorter than the panels 2, 3 and 4, in Figs. 14 and 16 I have shown the panel 5 as of the same length as these panels. Either arrangement can be employed, as desired.

So far as the functioning of the measuring device is concerned the two arrangements are identical, but the modified method of gluing, as shown in Figs. 15 and 16, results in decreasing the number of thicknesses of material when the device is in collapsed form. By reference to Fig. 3 it will be seen that in the region of the adhesive 4^a there are three superposed thicknesses of material, while by reference to Fig. 15 it will be seen that in the modified arrangement, there are only two thicknesses. This reduction in the number of thicknesses of material may be advantageous when the collapsed boxes are packed in bales or bundles for shipment.

What I claim is:

1. A dispensing package comprising a rectangular box having side, edge and end walls, and provided near one corner with a discharge opening, and measuring means contained within the box adjacent the corner having said opening, said means including a pair of spaced partition walls, relatively short as compared with the length of the box, secured to one of two opposite side walls of the box and extending between said side walls parallel with the edge walls and with each other.

2. A dispensing package comprising a rectangular box having side, edge and end walls, and provided near one corner with a discharge opening, and measuring means contained within the box adjacent the corner having said opening,

said means including a pair of spaced partition walls relatively short as compared with the length of the box, secured to one of two opposite side walls of the box and extending between said side walls parallel with the edge walls and with each other, the partition nearest said opening being imperforate and extending substantially to the end wall of the box adjoining said measuring means, and the other partition having its edge spaced from said end wall to provide a passageway therebetween, and means beyond the inner end of said first partition wall bridging the space between said last mentioned partition wall and the adjacent edge wall with which it is parallel.

3. A dispensing package comprising a rectangular box having side, edge and end walls, and provided near one corner with a discharge opening, and measuring means contained within the box adjacent said opening, said means including a pair of spaced, parallel partition walls fixedly secured to one of two opposite side walls of the box and extending between said side walls parallel with and spaced from the edge walls, the partition nearest said opening extending substantially to the end wall of the box, and the other partition having its edge spaced from said end wall to provide a passageway therebetween, and means positioned beyond the inner end of said first mentioned partition wall for closing the space between said last mentioned partition and the adjacent edge wall with which it is parallel.

4. A dispensing package comprising a rectangular box having side walls and relatively narrow edge walls, and provided near one corner with a discharge opening, and measuring means contained within the box wholly adjacent said corner, said means including a pair of spaced partition walls, relatively short as compared with the length of the box, anchored at one side to one of the opposite side walls and extending across the box parallel with the edge walls and with each other.

5. A dispensing package comprising a rectangular box having side walls and relatively narrow edge walls, and provided near one corner with a discharge opening, and measuring means contained within the box adjacent said corner, said means including a pair of spaced partition walls anchored at one side only to one of the opposite side walls and extending across the box parallel with each other, the other side of said partition walls being unattached to the box walls, and means at the unattached side of said partition walls for maintaining them parallel with said edge walls.

6. A dispensing package comprising a rectangular box having side walls and relatively narrow edge walls, and measuring means contained within the box adjacent one corner thereof, said means including a pair of spaced partition walls anchored at one side only to one of the opposite side walls and extending across the box parallel with each other, the other side of said partition walls being free from the box walls, and means at the free side of said partition walls abutting the adjacent edge wall to maintain said partition walls parallel with said edge walls.

7. A dispensing package comprising a rectangular box having side walls and relatively narrow edge walls, and measuring means contained within the box adjacent one corner thereof, said means including a pair of spaced, parallel partition walls fixed to one of the opposite side walls and extending across the box parallel with and

spaced from the edge walls, and a third partition wall extending from the end of that one of the pair farthest from the adjacent edge wall to said edge wall, and anchored thereto, said third wall being positioned beyond the inner end of the other of said partition walls.

8. A dispensing package comprising a rectangular box having side walls and relatively narrow edge walls, and measuring means contained within the box adjacent one corner thereof, said means including a pair of spaced partition walls anchored to one of the opposite side walls and extending across the box parallel with the edge walls and with each other, a third partition wall extending from the end of that one of the pair farthest from the adjacent edge wall to said edge wall, and means for so anchoring the free end of said third partition wall to said edge wall that it is capable of sliding laterally relative thereto.

9. As an article of manufacture, a folded blank box of the tubular type, in flat or collapsed condition, and having side and edge walls, said collapsed box having housed within it a plurality of superposed partition walls, said partition walls having both side edges hingedly supported at laterally and equally spaced points adjacent the opposite side walls of the box, whereby, when said box is opened up into tubular form, said partition walls are caused to swing about their hinges and assume a position extending across the box in spaced relation, parallel with each other and with the edge walls of the box, one of said partition walls having an extension, and means for anchoring the free end of said extension to an edge wall of the box, said partition walls and extension thus forming a chamber constituting measuring and dispensing means.

10. As an article of manufacture, a folded blank box of the tubular type, in flat or collapsed condition, and having side and edge walls, said collapsed box having housed within it a measuring device comprising a rectangular receptacle having side and edge walls in collapsed condition, one of said edge walls being rigidly secured to one of the side walls of the box and said receptacle overlapping portions of both the adjacent edge and side walls of the box, one of the side walls of said receptacle having an extension with a free edge, and means slidably confining said free edge against one wall of said box.

11. As an article of manufacture, a folded blank box of the tubular type, in flat or collapsed condition, and having side and edge walls, said collapsed box having housed within it measuring means comprising a plurality of superposed partition walls, means adjacent the opposite side walls of the box whereby both side edges of said partition walls are hingedly supported at laterally spaced points, one of said supporting means being fixed to one of said side walls, but the other of said supporting means being unattached to the box walls.

12. As an article of manufacture, a folded blank box of the tubular type, in flat or collapsed condition, and having side and edge walls, said collapsed box having housed within it a measuring cell comprising hingedly connected side and end walls, said cell being also in collapsed condition, with the side walls superposed, one of said side

walls having a longitudinal extension of equal width, means securing one edge wall of the cell to a side wall of the box at such a point that the hinges between said edge wall of the cell and the adjacent side walls thereof are parallel with but spaced from the fold line between said side wall of the box, and the adjacent edge wall thereof so that the superposed side walls of the cell, including said extension, overlie said fold line, and means slidably confining the free end of said extension to said adjacent edge wall of the box, whereby when said box is opened up to tubular condition said cell is also opened up into rectangular form with the side walls thereof parallel with and spaced from the adjacent edge wall of the box, and with said extension disposed at an angle between the side wall of the cell to which it is attached and the said adjacent edge wall of the box.

13. As an article of manufacture, a folded blank box of the tubular type, in flat or collapsed condition, and having side and edge walls, said collapsed box having housed within it a measuring cell comprising hingedly connected side and end walls, said cell being also in collapsed condition, with the side walls superposed, one of said edge walls having a lateral extension, means securing the other edge wall to a side wall of the box in such position that said superposed side walls of the cell overlie the adjacent edge wall of the box and the free end of said lateral extension lies substantially at the fold line between said edge wall of the box and the side wall of the box opposite that to which said cell is secured, whereby the free edge of said lateral extension is anchored in said fold line, and said cell is thus caused to open to rectangular form when said box is opened up to tubular condition.

14. A dispensing package comprising a rectangular box having side, edge and end walls, and provided near one corner with a discharge opening, and measuring means contained within the box adjacent said opening, said means including a pair of spaced fixed partition walls disposed parallel with and spaced from one edge wall of the box, the partition nearest said opening extending to the end wall of the box adjacent said opening, and the other partition having its edge spaced from said end wall to provide a passageway therebetween, and a third partition wall closing the space between said last mentioned partition and the adjacent edge wall with which it is parallel, and extending beyond the inner end of said first mentioned partition wall.

15. A dispensing package comprising a rectangular box having side walls and relatively narrow edge walls, and measuring means contained within the box adjacent one corner thereof, said means including a pair of fixed, spaced partition walls extending across the box parallel with and spaced from one of the edge walls, and a third partition wall extending from the end of that one of the pair farthest from the adjacent edge wall to said edge wall, and anchored thereto, said third partition wall forming a compartment communicating both with the space between said pair of walls and the space between the other of said pair and said edge wall.

ERNEST J. BISKAMP.
